UNITED STATES PATENT OFFICE.

JOHN F. DUFF, OF MURPHYSBOROUGH, ILLINOIS.

CAR-COUPING.

SPECIFICATION forming part of Letters Patent No. 352,526, dated November 16, 1886.

Application filed September 30, 1886. Serial No. 214,952. (No model.)

To all whom it may concern:

Be it known that I, JOHN F. DUFF, a citizen of the United States, residing at Murphysborough, in the county of Jackson and State 5 of Illinois, have invented certain new and useful Improvements in Car-Couplings; and I do hereby declare the following to be a full, clear, and exact description of the invention, such as will enable others skilled in the art to which 10 it appertains to make and use the same.

This invention has relation to car-couplers; and the object of the invention is to provide an automatic coupler of simple construction and operation, and cheap and durable.

15 With these general objects in view the invention consists in certain features of construction hereinafter specified, and particularly pointed out in the claims.

Referring to the drawings, Figure 1 is a 20 plan of a car-coupler constructed in accordance with my invention. Fig. 2 is a longitudinal central vertical section on the line X of Fig. 1. Figs. 3 and 4 are top and bottom perspectives of the locking pawl; and Fig. 5 25 is a detail in perspective of the lifting or operating lever.

Like letters of reference indicate like parts in all the figures of the drawings.

A represents the draw-head of a car-coupler, and B the draw-bar. The head A is 30 formed with the recess A' and the integral cross-bar A² at the top thereof.

C represents the locking-pawl, the forward 35 end of which is provided with a curved or semicircular recess, C', which is adapted to fit and revolve partly around the cross-bar A². The pawl C is also formed with the locking-shoulder C², into which an ordinary connecting-link is adapted to take, and at the upper rear end of the pawl is formed an operating-shoulder, C³.

Within a recess at the rear end of the recess or chamber A' is pivoted an operating cam-lever, D, formed with the cam portion 45 D', which cam portion is located directly under and against the operating-shoulder C³. The operating-shoulder C³ is inclined transversely across the rear end of the pawl, which pawl is pivotally held within the recess by 50 means of a pin or pivot, D².

This being the construction, the operation of coupling and uncoupling is as follows: The weight of the pawl is of course sufficient to cause it to rest upon the bottom of the draw-

head, and an approaching link passes within 55 the chamber A' and against the beveled or slanting front face of the pawl when the same is caused to rise, allowing the link to pass to the rear end of the locking-chamber, whereupon the pawl drops by gravity, and the link 60 is held in place by means of the locking shoulder or lug C² of the pawl. The cars are now coupled, and that automatically. To uncouple the same it is only necessary to raise the operating-lever D, which raises or swings 65 the cam portion D' upwardly, which, coming in contact with the slanting operating-shoulder C³ of the pawl, causes the pawl to rise and allow the link to be withdrawn.

If desired, a chain or rope may be connected 70 to the free end of the lever D, and may extend to any convenient part of the platform or of the car, whereby the operation of uncoupling may be carried on without the necessity of leaving the platform.

75 By reason of the loose mounting of the pawl C, it is evident that the same may easily and quickly be replaced when worn.

Having described my invention and its operation, what I claim is—

80 1. In a car-coupler, a draw-head recessed and formed with a transverse bar, in combination with a gravity locking-pawl formed with a locking-shoulder and operating-shoulder at its rear end, and with a cam-lever pivoted in said chamber and under and in contact with said operating-shoulder, substantially as specified.

85 2. In a car-coupler, the combination of a draw-head formed with a recess and transverse bar, with a locking gravity-pawl loosely mounted on the transverse bar and removable from the chamber, and formed with a locking-shoulder and a slanting operating-shoulder, and with a cam-lever pivoted in said 90 recess and in contact with the operating-shoulder, substantially as specified.

95 3. The combination of the draw-head A, having the recess A' and cross-bar A², with the pawl C, having the shoulders C² C³, and the pivoted cam-lever D, formed with the cam portion D', substantially as specified.

In testimony whereof I affix my signature in presence of two witnesses.

JOHN F. DUFF.
